W. K. HOWE

DETACHABLE UNIT CIRCUIT CONTROLLER FOR INTERLOCKING MACHINES

Filed Nov. 2, 1920

By his Attorney
Winthrop K. Howe, Inventor
Neil D. Weston.

UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

DETACHABLE-UNIT CIRCUIT CONTROLLER FOR INTERLOCKING MACHINES.

Application filed November 2, 1920. Serial No. 421,407.

To all whom it may concern:

Be it known that I, WINTHROP K. HOWE, citizen of the United States, residing at Rochester, in the county of Monroe and 5 State of New York, have invented certain new and useful Improvements in Detachable-Unit Circuit Controllers for Interlocking Machines, of which the following is a specification.

10 This invention relates to unit circuit controllers for electric interlocking machines. In the interlocking machines now commonly in use, the several circuit controllers for governing the operation of switches and 15 signals are of the unit construction and are arranged horizontally in a row or bank. Each of these circuit controllers has connected to it a number of wires; and on account of the general arrangement found es- 20 sential in practice, these wires are run underneath the bank of the circuit controllers, usually to some suitable terminal board. Other wires also run from the terminal board to the indication magnets and other 25 electrical devices of the interlocking machines, with the result that the space underneath the circuit controllers is taken up with a large number of wires. Heretofore it has been the common practice to fasten 30 the unit circuit controllers to their frame by screws or the like, accessible only from underneath the circuit controllers. With this arrangement, when it becomes desirable to replace a worn or defective contact spring, 35 or other part of the circuit controller unit, it is very difficult to do so on account of the number of wires in the way. Also, the disconnection or displacement of wires likely to occur during this operation would 40 sometimes result in false operation of the machine and serious accidents, so that it has been considered desirable by some railroads to cut the whole machine out of service when making such repairs, but this causes delays 45 and results in postponing the needed repairs and adjustments until convenient to cut the machine out of service.

With a view of remedying these difficulties, the primary object of the present invention is to devise an improved construction 50 of a unit circuit controller which can be easily and quickly detached for repair or adjustment without deranging the wires of the machine or interfering with its operation.

Other specific objects and advantages of my improved construction will appear hereinafter as the description progresses; and the novel features of the invention will be pointed out in the appended claims. 60

I have devised my improvement in connection with an interlocking machine of well known construction, familiar to those skilled in the art, and consequently I have shown in the accompanying drawings only those parts 65 of the complete machine necessary to explain the nature of my improvement.

In these drawings, Fig. 1 is a plan view of two circuit controller units embodying the present invention, showing parts of their 70 supporting brackets and the levers by which these circuit controllers are operated;

Fig. 2 is a side view of one of the circuit controller units, and partly in vertical section, as indicated by the line 2—2 in Fig. 1; 75

Fig. 3 is a transverse section on the line 3—3 in Fig. 1; and

Fig. 4 is a modification showing my invention applied to a four-tier circuit controller. 80

Referring to the accompanying drawings, F designates a portion of the brackets of an interlocking machine which carry the row of unit circuit controllers. In practice several of these brackets F are arranged vertically at intervals lengthwise of the machine. At the upper edges of the brackets F are fastened by screws or the like (not shown) two parallel bars 1 and 2 to which the circuit controller units are fastened in 85 a manner hereinafter explained.

Each circuit controller unit comprises a frame made up of two end blocks B, of hard rubber or other suitable insulating material, and upper and lower guide bars 3 and 4, 95 which are fastened to said end blocks by screws 5. Two or more pairs of contact springs SS are secured to each end block. These contact springs are constructed the same, and each is provided with a flange 6 at 100 one end, and is fastened at that end to a corresponding block by two screws 7 and 8. The body of each contact spring S is bent back upon itself as shown in Fig. 1.

A contact block C, of hard pressed fiber, 105 or other suitable insulating material, is formed with grooves in its upper and lower ends fitting over the guide bars 3 and 4. The corners of this contact block C are under-cut or rabbeted as shown in Fig. 1, to 110

receive the bent ends of contact pieces 9. One end of an operating rod 10 passes through the contact block C and is adjustably clamped thereto by nuts 11. This operating rod 10 passes through a large hole 12 in one end block B, and is formed at its free end with an eye which fits over a pin 13 in the lever L, said operating rod being held in place by a suitable cotter pin.

10 The circuit controller units above described are arranged in rows or banks as shown in Fig. 1, and since space is an important matter in machines of this kind, the units are placed as close together as practicable. In order to prevent improper electrical connection between the parts of adjacent units, an insulator 14, with grooves to receive the heads of the screws 8, is fitted between the end blocks B of adjacent units, 15 and a panel 15, preferably of glass, fits in narrow grooves in said insulators.

Each end block B is fastened by a screw 16 to the corresponding bar 1 or 2. This screw 16 is provided with a suitable lock washer; and its head bears against a square spacer 17, preferably made of suitable insulating material, which is seated in a recess or groove in the bottom of the opening 12 in the corresponding end block, as shown 20 in Fig. 3. In the two-tier circuit controller shown in Figs. 1 and 2, each end block B is provided with a hole or passage 18 above the screw 16, so that a screw-driver or similar tool may be inserted from above, and the 25 screws 16 taken out. The same construction is also used in the three-tier circuit controller, that is, one having three pairs of contact springs, one above the other; but where the circuit controller has four or more 30 tiers, as shown in Fig. 4, a horizontal guide rod 19 for the contact block C is used. This guide rod is fixed to said contact block C and guided in holes in the end blocks B. In this case, an inclined groove or channel 35 40 45 50 55 60 65 70 75 80 85 90 95 100 105 110 115 120 125 130 135 140 145 150 155 160 165 170 175 180 185 190 195 200 205 210 215 220 225 230 235 240
